(57) **CLAIM**

The ornamental design for a vehicle go button, as shown and described.

DESCRIPTION

It is related to application Ser. No. 29/714,611, entitled Vehicle Go Button; and to application Ser. No. 29/714,644, entitled Vehicle Pull Over Button, both filed concurrently herewith. This application is also related to application Ser. No. 29/491,937, entitled Autonomous Vehicle Overall Interior, filed May 27, 2014 and issued as U.S. Design patent No. D770,349 on Nov. 1, 2016; to application Ser. No. 29/547,496, entitled Autonomous Vehicle Seat, filed Dec. 4, 2015 and issued as U.S. Design patent Ser. No. D778,080 on Feb. 7, 2017.

FIG. 1 is a top view of an image for a vehicle go button according to a first embodiment of our design; and, FIG. 2 is a top view of an image for a vehicle go button according to a second embodiment of our design.

The features shown in broken lines are environmental only and form no part of the claimed design. The portions shown in a pattern or patterns of stipple illustrate areas of contrasting appearance.

As shown in the figures, the vehicle go button is planar.
